UNITED STATES PATENT OFFICE.

SAMUEL RITCHIE TUGGLE AND CHARLES WILLIAM DOERING, OF
HOUSTON, TEXAS.

JACK.

SPECIFICATION forming part of Letters Patent No. 732,142, dated June 30, 1903.

Application filed October 24, 1902. Serial No. 128,569. (No model.)

To all whom it may concern:

Be it known that we, SAMUEL RITCHIE TUGGLE and CHARLES WILLIAM DOERING, citizens of the United States, residing at 5 Houston, in the county of Harris and State of Texas, have invented new and useful Improvements in Jacks, of which the following is a specification.

Our invention relates to jacks such as are 10 designed to be operated by fluid-pressure—*i. e.*, water, air, or other fluid under pressure; and it has for its object to provide a telescopic fluid-pressure jack designed more particularly for use in conjunction with locomotive driving axles and wheels, as herein-after pointed out.

The invention will be fully understood from the following description and claims when taken in connection with the accompanying 20 drawings, in which—

Figure 1 is a vertical section of our improved jack as it appears when raised to the full extent. Fig. 2 is an enlarged view, partly in section and partly in elevation, illustrating 25 the members of the jack as nested; and Fig. 3 is a detail section taken in the plane indicated by the broken line 3 3 of Fig. 1 and illustrating the manner in which we prefer to mount the jack on a carriage.

Similar letters of reference designate corresponding parts in all of the several views of the drawings, referring to which—

A is the lower cylindrical member, B C the upper cylindrical members, and D the 35 piston, of our improved jack. The member A is preferably made up of a lower head or bed-plate *a*, a cylindrical body *b* of less diameter than said head arranged thereon and having an interior flange *c* and an exterior 40 flange *d* at its upper end, and rods *e*, interposed between and connecting the head *a* and the flange *d*. The said member A is internally of a size to receive a flange *f* at the lower end of the member B, which in turn is internally of a size to receive a flange *g* at the 45 lower end of the member C.

The members B C are provided at their upper ends with inwardly-directed flanges *h*, and these flanges and the flange *c* of member 50 A are provided with apertures *i*, as shown, for the escape of air incident to the raising

of the jack. The member C is also provided at its upper end with a ring *j*, which projects beyond its side and is adapted when the members are nested, Fig. 2, to bear on the upper 55 end of the member B for a purpose herein-after described.

The piston D is of a size to move in the member C and is provided with a rod *k*, preferably hollow, which extends through the 60 upper end of the said member. On this rod *k* is secured a socket *l*, which rests on the member C, Fig. 2, and in which is pivotally held by a pin *m* or other means a rounded protuberance *n* at the under side of a jack- 65 plate *p*. This jack-plate *p* has concavities *p'* in opposite side walls and contains a hardwood filling *q*, concave at its upper side, and roller *r*, the latter being arranged in recesses *r'* in the filling at opposite sides of the 70 center of the jack-plate and being designed to adjust themselves to locomotive driving-axles and for the purpose of lowering the center of gravity of the driving-wheels. The hardwood filling *q* serves to support the rollers *r* throughout the length thereof when the 75 weight of a locomotive-axle is imposed on said rollers, and consequently removes strain from the bearings of the roller in the jack-plate.

At their lower ends the cylindrical members B C and the piston D are provided with gaskets *s*, preferably of leather, which are secured between the said ends and follower-rings *t*, connected thereto.

E is a three-way cock, F a pressure-gage, 85 and G an exhaust-valve. The three-way cock is connected with the pressure-gage and the bottom of the member A by a pipe *u*, with the exhaust-valve G by a pipe *v*, and with a source of fluid-pressure supply (not shown) 90 by a pipe *w*. From this it follows that when the three-way cock is adjusted to effect connection between the source of fluid-pressure supply and the interior of the member A the jack will be raised or extended, and when 95 said cock is adjusted to connect the interior of the member A and the exhaust-valve G and the said valve G is opened the jack will be lowered. It will also be observed that by opening the valve G to a greater or less extent the lowering of the jack and the burden imposed thereon may be readily regulated.

The ring *j* on the cylindrical member *C* serves by engaging the upper end of the member *B*, Fig. 2, to admit of the combined lifting power of the members *B* and *C* and the 5 piston *D* being utilized.

H H are the suspension-rods disposed in lugs *x* at the under side of the bed-plate *a* of the lower member *A* of the jack, *I I* axles having wheels *J* at their ends arranged to 10 travel on rails *K*, and *L L* hangers, preferably U-shaped, connecting the suspension-rods and the axles. The suspension-rods, axles and wheels, and the hangers constitute the carriage on which we prefer to mount our 15 improved jack, and when the said carriage is arranged on a track, as shown, it will be observed that the jack may be moved with but a minimum amount of effort.

Our improved jack has been operated in 20 connection with a drop-pit having movable sides, being used to lower locomotive driving axles and wheels, which are then run forward on a lower track in the pit and raised by an air-hoist to an upper track. When 25 thus used, the jack is capable of raising and lowering the driving axles and wheels of the heaviest locomotive and is a great labor-saver.

While our improved jack is designed more particularly for raising and lowering locomotive driving axles and wheels, it may obviously be used to advantage for other purposes when desired.

We have entered into a detailed description of the construction and relative arrangement of the parts embraced in the present 35 and preferred embodiment of our invention in order to impart a full, clear, and exact understanding of the same. We do not desire, however, to be understood as confining ourselves to such specific construction and arrangement of parts, as such changes or modifications may be made in practice as fairly fall within the scope of our invention as claimed.

45 Having described our invention, what we claim, and desire to secure by Letters Patent, is—

1. A telescopic, fluid-pressure jack comprising a cylindrical member, a piston movable in the cylindrical member, and having a rod extending through one end of the same, a jack-plate arranged on the piston-rod, a wood filling arranged in the jack-plate; said filling being concave at its upper side, and having recesses in said side at opposite sides of the center of the jack-plate, and rollers mounted in the jack-plate, and disposed in said recesses of the filling, and resting on the filling.

60 2. A telescopic, fluid-pressure jack comprising a cylindrical member, a piston movable in the cylindrical member, and having a rod extending through one end of the same,

and also having a rounded socket on said rod, a jack-plate having a rounded protuberance 65 pivotally secured in said socket, and also having concavities in opposite side walls, a wood filling arranged in the jack-plate; said filling being concave at its upper side, and having recesses in said side at opposite sides of the 70 center of the jack-plate, and rollers mounted in the jack-plate, and disposed in said recesses of the filling, and resting on the filling.

3. The telescopic, fluid-pressure jack described, comprising a lower cylindrical member made up of a bed-plate having depending apertured lugs, a body of less diameter than the bed-plate, arranged thereon, and having an interior apertured flange and an exterior flange at its upper end, and rods connecting 80 the bed-plate and said exterior flange of the body, one or more upper cylindrical members arranged to nest in the lower member, and having inwardly-directed apertured flanges at their upper ends, and also having outwardly-extending flanges at their lower ends, a piston movable in the upper member, and having a rod extending through the upper end thereof, follower-rings connected to the lower ends of the upper cylindrical members 90 and the piston, gaskets secured between said rings and the upper members and piston, means for supplying fluid-pressure to the lower cylindrical member, axles equipped with wheels, suspension-rods disposed in the 95 depending lugs of the bed-plate, and hangers connecting the axles and said suspension-rods.

4. In a telescopic, fluid-pressure jack, the combination of a lower cylindrical member 100 comprising a bed-plate, a body of less diameter than the bed-plate, arranged thereon, and having an interior apertured flange, and an exterior flange at its upper end, and rods connecting the bed-plate and said exterior flange 105 of the body, one or more upper cylindrical members arranged to nest in the lower member, and having inwardly-directed apertured flanges at their upper ends, and also having outwardly-extending flanges at their lower 110 ends, a piston movable in the upper member, and having a rod extending through the upper end thereof, follower-rings connected to the lower ends of the upper cylindrical members 115 and the piston, gaskets secured between said rings and the upper members and piston, and means for supplying fluid-pressure to the lower cylindrical member.

In testimony whereof we have hereunto set our hands in presence of two subscribing witnesses.

SAMUEL RITCHIE TUGGLE.
CHARLES WILLIAM DOERING.
